(57) CLAIM

The carrier device, substantially as shown in the drawings.

DESCRIPTION

FIG. 1 is a front elevation view of a carrier device for an intravaginal insert for cattle or the like to induce oestrus showing my new design;

FIG. 2 is a side elevation view thereof;

FIG. 3 is an other side elevation view thereof;

FIG. 4 is a bottom plan view thereof;

FIG. 5 is a top plan view thereof;

FIG. 6 is a front and side perspective view thereof;

FIG. 7 is an exploded front and side perspective view thereof; and,

FIG. 8 is a front and side perspective view of the insert shown separately for clarity of illustration.
